United States Patent Office

Des. 207,189
Patented Mar. 14, 1967

207,189

JAR

Ernest F. Thomson, 212 Burns St., Forest Hills, N.Y.
11375, and Carl G. Hebel, 290 Jefferson Ave., Haworth,
N.J. 07641

Filed July 31, 1964, Ser. No. 81,089

Term of patent 14 years

(Cl. D58—25)

FIG. 2

FIG. 1

FIG. 4

FIG. 3

FIG. 1 is a side elevational view of a jar embodying our new design;

FIG. 2 is a top plan view;

FIG. 3 is a bottom plan view; and

FIG. 4 is an end elevational view thereof;

FIG. 5 is a side elevational view of another embodiment of our new design;

FIG. 6 is a top plan view;

FIG. 7 is a bottom plan view; and

FIG. 8 is a side elevational view thereof.

The dominant features of our design reside in the portions shown in full lines.

We claim:

The ornamental design for a jar, as shown and described.
